AMOS F. DIXON, OF NEWARK, NEW JERSEY, ASSIGNOR, BY MESNE ASSIGNMENTS, TO
WESTERN ELECTRIC COMPANY, INCORPORATED, A CORPORATION OF NEW YORK.

PRINTING-TELEGRAPH SYSTEM.

1,271,141.

Specification of Letters Patent. Patented July 2, 1913.

Application filed April 15, 1915. Serial No. 21,542.

To all whom it may concern:

Be it known that I, AMOS F. DIXON, a citizen of the United States, residing at Newark, in the county of Essex and State of New Jersey, have invented certain new and useful Improvements in Printing-Telegraph Systems, of which the following is a full, clear, concise, and exact description.

This invention relates to printing telegraph systems and its principal object is to provide an improved system, particularly applicable where the various stations are separated by comparatively short distances.

The invention finds an especially ready field in large mercantile or manufacturing establishments where it is necessary for a number of departments to receive duplicate copies of orders, etc., the custom in the past having been to prepare the proper number of duplicates on a typewriting machine, the copies then being delivered to the necessary points by messengers. This is an expensive, slow and unreliable method of communication which the present invention, by providing an instantaneous, exact and inexpensive duplication of records at the desired points is designed to supersede. The operations are performed electromechanically and may be controlled from a single central point or the system may be so arranged as to provide for intercommunication as best suits the particular conditions to be fulfilled.

In accordance with its general features, the invention contemplates a controller adapted to selectively supply current to a plurality of transmission lines, each line being associated with one of a plurality of selecting electro-mechanisms, the cooperation of which causes the performance of any desired operation as, for example, the selecting of a type, the closing of a switch, etc. An improved arrangement is provided whereby the apparatus is returned to normal, the controller being prevented from attaining this condition until the selecting apparatus at all of the stations has performed its proper functions, thus preventing incomplete or otherwise inaccurate records from being produced at any point. The use of a plurality of lines renders it unnecessary to employ a sequence of impulses, consequently eliminating expensive and complicated apparatus in those fields where the

various stations are separated by such short distances that the additional line construction is less expensive and objectionable than impulse producing apparatus.

The above and other objects of this invention will be fully set forth in the following description and claims, and will be more readily understood by reference to the accompanying drawing in which Figure 1 shows the system of connections and part of the mechanism of the preferred embodiment diagrammatically and Fig. 2 is a view of a type or operation controlling lever coöperating with the selecting disks.

Two stations, A and B, are shown interconnected by a plurality of transmission lines 5, 6, 7, 8 and 9 and a control conductor 10. There may be as many stations as desired, but since they will all be similar to A and B, there is no necessity for showing more. Preferably at one of the stations, as for example station A, there is a controller for selectively influencing the flow of current over lines 5 to 9 inclusive, although if no home record is desired, the controller may be located at some other point. This controller consists of a plurality of control switches 15, 16, 17, 18 and 19, each associated with one of the lines 5, 6, 7, 8 and 9 respectively. It is likewise provided with a power switch 20, associated with a grounded source of energy 21 and a pair of locking switches 22 and 23. The fixed contacts of switches 22 and 23 are connected to one terminal of a locking magnet 24, the other terminal of which is connected to a grounded source of energy 25. The movable contact of switch 23 is joined to conductor 10.

Control switches 15 to 19 inclusive are selectively actuated by any of the well known means, as for example a plurality of character keys arranged in the form of an ordinary typewriter keyboard, or an automatic actuator controlled by a perforated paper tape or the like. In either case it is preferable to have this apparatus also operate switches 20 and 22. Locking magnet 24 may be arranged in any of the well known ways, so that when it is energized by the closing of switch 22, it holds all of the switches 15 to 19, which have been actuated, in this condition, retains switch 20 in closed condition and by also holding switch 23 in closed condition establishes a holding circuit for

itself, independent of switch 22 which need be closed only momentarily, as will be hereinafter explained.

Each of the lines 5 to 9 inclusive is associated at each station with an individual selecting device. These devices comprise a plurality of electromagnets 35, 36, 37, 38 and 39 which, with the associated selecting disks 45, 46, 47, 48 and 49 connected to and movable by the respective electromagnets, through the agency of levers 55, 56, 57, 58 and 59, respectively, form a selecting apparatus for controlling the selection of the proper type or operation. Disks 45 to 49 inclusive are adapted to be rotated about their centers and are each provided on their peripheries with a plurality of notches 60. Passing through the center of the disk is a rotatable shaft 61, carrying a type wheel 62 and a stop arm 63. The disks and their notches 60 coöperate with a plurality of spring tensioned levers 64, pivoted in a circle about the type shaft 61, and of which some are adapted to stop the type wheel in any desired position, and others are adapted to control circuit contacts, when presented with a continuous vertical row of notches, as will be hereinafter explained.

Normally, the type controlling levers are depressed below the level of stop arm 63, the operation controlling levers are held in an inactive position and the vertical arms of all of these levers are held away from the peripheries of the disks by release and restoring levers 70 which are controlled by a pair of release magnets 71. The inner circular shaped ends of levers 70 are normally held depressed by suitable retractile springs 72, but this force is overcome and the inner ends are raised when release magnets 71 are energized.

One of the terminals of the windings of release magnets 71 is connected to a grounded source of energy 75 and one of the levers 70 is provided with a pair of switches 76 and 77. These switches normally stand open, but are adapted to be closed when release magnets 71 are energized. The fixed contact of switch 76 is connected to an armature 78 of a release control relay 79, while the movable contact thereof is connected to the terminals of release magnets 71 and a front contact coöperating with the armature 78. The fixed contact of switch 77 is connected to a grounded source of energy 82 and its movable contact is grounded through the winding of a start control relay 83. Armature 78 of release control relay 79 is likewise connected to conductor 10 and a back contact coöperating with an armature 84 of a clear-out relay 85. Release control relay 79 is also provided with an armature 86 connected to a holding winding 87 of clear-out relay 85 and coöperating with a front contact connected by a grounded

source of energy 88. Clear-out relay 85 is provided with an operating winding 90, one terminal of which is connected to a grounded source of energy 91, the other terminal being associated with contacts controlled by the levers 64. Some of these contacts are formed by the engagement of the character-selecting levers 64 and stop arm 63, while others are provided by suitable switches controlled by the operation selecting levers 64, as will be hereinafter explained.

In the circuits including the stop arm 63 is a printing magnet 92 and a space-lock relay 93. The space-lock relay 93 controls the action of a spacing magnet 94 by completing a circuit therethrough from a grounded source of energy 95. Start control relay 83 causes the energization of a start magnet 96 by completing a circuit therethrough from a grounded source of energy 97 and when this magnet is energized, it withdraws a suitable pawl from a ratchet-wheel on shaft 61, allowing the shaft to be rotated by a spring which is always tending to rotate the type-wheel 62 in the direction of the arrow as disclosed in U. S. Patent 1,103,133, issued July 14, 1914.

In addition to the apparatus already described, there is a line feed magnet 100 for feeding the paper line by line; a shift magnet 101 for causing the type-wheel to be raised so that its lower row of characters is in printing position and a carriage return magnet 102 for causing the paper carriage 100 to be returned to the beginning of a line of print. These magnets are respectively controlled by switches 105, 106 and 107 which are actuated by certain of the disk selected levers 64. The apparatus associated with 105 and controlled by the start, space, printing, line feed, shift and carriage return magnets may be of any desired and appropriate form of construction, the preferred form being that shown in the above mentioned U. S. Patent.

The operation of the system is as follows:—

When the keyboard or automatic device selectively actuates switches 15 to 19 inclusive and closes switches 20 and 22, a circuit is completed from grounded source 21, switch 20, through the operated contacts 15 to 19 inclusive, the corresponding magnets 35 to 39, inclusive, and release control relay 79 to ground. A circuit is also closed from grounded source 25 through locking magnet 24 and switch 22 to ground. The first circuits traced cause the selected magnets 35 to 39 inclusive to rotate their corresponding disks 45 to 59 inclusive through the agency of levers 55 to 59 inclusive, resulting in a continuous row of notches 60 being presented before only one of the type or operation selecting levers 64. These cir-

cuits also cause the release control relay 79 to pull up its armatures 78 and 86 whose functions will be presently described. The circuit through locking magnet 24 causes this magnet through the agency of holding mechanism to hold all of the operated switches 15 to 19 inclusive and switch 20 in closed position and by closing switch 23, completes a holding circuit for itself from grounded source 25 through switch 23, conductor 10 and the back contact and armature 84 of the clear-out relay 85.

The attraction of armature 78 of release control relay 79 completes circuits from grounded sources 75 through the release magnets 71, front contact and armature 78 of release control relay 79 and back contact and armature 84 of clear-out relay 85 to ground. The completion of this circuit causes release magnets 71 to elevate the inner ends of release levers 70, allowing all of the levers 64 to attempt to enter the slots 60. All but one of these levers, however, as hereinbefore explained, are prevented from so moving by the unnotched portion of the periphery of at least one of the disks 45 to 49 inclusive.

The movement of the right-hand release lever 70 closes switches 76 and 77. Switch 76 completes circuits from sources 75 through release magnets 71 to ground at armature 84 independent of the front contact of release control relay 79 so that the selected lever 64 will not be prematurely depressed but this action being now dependent upon the energization of clear-out relay 85, as will be hereinafter explained. The closing of switch 77 completes a circuit from grounded source 82 through the start control relay 83. Start control relay 83, if the selection has been a type selection, in pulling up its armature completes a circuit from grounded source 97, switch 105, start magnet 96 to ground at armature 84 of clear-out relay 85. The start magnet thereupon allows the type wheel 62, to be rotated in the direction of the arrow and since the inner end of one of the levers 64 has been elevated, arm 63 will be engaged thereby and the type wheel will be arrested in position to print the desired character. The engagement of the selected lever 64 and arm 63 completes a circuit from grounded source 91, operating winding 90 of clear-out relay 85, operating winding of the space-lock relay 93, printing magnet 92, arm 63 and lever 64 to ground. Thereupon printing magnet 92, through the agency of the printing platen, forces the paper against the desired type while the energization of space-lock relay 93 completes a circuit from grounded source 95 through the space magnet 94 which initiates the movement of the paper carriage for spacing for the next character to be selected. Although the printing magnet 92

and the space-lock relay 93 are in the same circuit, the time necessary for the space-lock relay to attract its armatures, energize the space magnet, and for the space magnet to cause the spacing mechanism to perform the desired function, delays the spacing operation until after the printing has been completed.

The energization of clear-out relay 85, due to the circuit just traced, through its operating winding 90, causes the attraction of armature 84 which, if the release control relay is still energized, completes a holding circuit from grounded source 88, front contact and armature 86 of release control relay 79, holding winding 87 of clear-out relay 85 to ground at armature 84. The attraction of armature 84 also interrupts the previously traced circuits through switch 76 and release magnet 71, that through switch 23 and the locking magnet 24, and also that through the start magnet 96. Springs 12 thereupon depress levers 70 and levers 64 are all returned to normal. Shaft 61 is also held from rotation by the pawl controlled by magnet 96. If now, switch 22 has been opened by the controller mechanism, the interruption of the holding circuit through magnet 24 causes the release of the selected switches 15 to 19, inclusive, together with switches 20 and 23. The opening of selected switches 15 to 19 inclusive and switch 20 interrupts the circuit through the selected magnets 35 to 39 inclusive, and the release control relay 79, whereupon the holding circuit through the holding winding 87 of clear-out relay 85 is broken at armature 86 of release control relay 79 and all of the apparatus will be returned to normal, a character will have been printed and the paper carriage has been moved to present a clean space for the next character.

In case it is desired to space the paper carriage without printing, switches 15 to 19 inclusive will be so selectively closed that disks 45 to 49 inclusive will be moved to present a continuous row of notches before the selecting lever 64 which controls the actuation of spacing switch 110. The closing of this switch closes a circuit from grounded source 91 through the operating winding 90 of clear-out relay 85, operating winding of space-lock relay 93 to ground. Space lock relay 93 and clear-out relay 85 perform their functions as hereinbefore described, the only difference in the operations being that armature 84 of clear-out relay 85 is energized too soon to allow the energization of start magnet 96 and the type shaft is not released.

The operation of the line feeding mechanism is initiated by the selection of switch 105 whose operation closes a circuit from grounded source 97 through the line feed magnet 100, and opens the previously traced circuit through the start magnet 96. The en-

ergization of line feed magnet 100 causes the paper to be fed up one line and the energization of clear out relay 85, which returns the apparatus to normal as hereinbefore described. The breaking of the circuit through start magnet 96 prevents the type shaft from rotating during the feeding operation.

In order to print from the lower row of type, shift switch 106 is selectively closed, 10 which results in the energization of shift magnet 101. The action of this magnet, besides shifting the type wheel completes a holding circuit from grounded source 111 through an unshift switch 112 so that when 15 once shifted, the type wheel will remain in this condition until the disks are so moved that unshift switch 112 is actuated, whereupon the previously traced holding circuit through shift magnet 101 is broken.

20 The paper carriage is returned to the beginning of a line by the actuation of carriage return switch 107, resulting in the energization of carriage return magnet 102. This magnet, besides causing the return of the 25 carriage, completes a holding circuit for itself from grounded source 111 through a paper carriage switch 115, which switch is opened when the carriage reaches its normal position. The premature arresting of the 30 carriage is therefore prevented.

In the foregoing description, the operations of the apparatus at station A have been set forth but the same actions have taken place at station B and all other stations 35 associated with lines 5 to 9 inclusive. It will, therefore, be readily apparent that the de-energization of locking magnet 24 is dependent upon the operation of all of the clear-out relays 85, so that a given selection of the 40 switches 15 to 19 inclusive will be maintained until the desired character or operation is performed and the clear-out relay of the slowest printer has attracted its armature 84.

Thus the incomplete operation of any printer is prevented.

What is claimed is:

1. A printing telegraph system comprising a current controller, a plurality of transmission lines associated therewith, a plurality of electrical selecting devices, one associated with each said line, and energized solely thereby, whose coöperation causes the performance of any desired operation, and means operated first by said controller and later through the influence of said selecting devices for restoring the controller and the selecting devices to normal after the completion of an operation.

2. A printing telegraph system comprising a plurality of transmission lines for interconnecting a plurality of stations, selecting apparatus at each station for performing the desired operations, a current controller associated with said lines for effecting the operation of said apparatus, and a self-locking clear-out relay coöoperating with said system for restoring the controller and the selecting apparatus to normal after the completion of an operation.

3. A printing telegraph system comprising a plurality of transmission lines, selecting apparatus at each station for performing the desired operations, a current controller associated with said lines for effecting the operation of said apparatus, a release control relay-controlling the initiation of the performance of the selecting operation, and a clear-out relay associated with said release control relay, said apparatus and said controller for restoring the controller and the selecting apparatus to normal after the completion of an operation.

In witness whereof I hereunto subscribe my name this 13th day of April, A. D. 1915.

AMOS F. DIXON.
